UNITED STATES PATENT OFFICE

JOSEPH MESSING, OF PHILADELPHIA, PENNSYLVANIA

NEEDLE

Application filed March 13, 1929. Serial No. 346,563.

My invention relates to improvements in a knitting needle particularly adapted for mending fabric and especially for repairing runs in stockings.

The object of my invention is to construct a needle which may be operated rapidly and which does not require skill in guiding the needle through the operations to form the loops in the threads of the fabric for repairing the same; a still further object is to provide a latch needle with a stop for limiting the distance the needle may be inserted into the fabric and preventing the straight, or tight, threads of the fabric from passing over the point of the latch and permitting the loop to slide over the point of the latch when it is in the open position; a still further object is to provide a needle having a relatively long hook member, which forms a guide permitting the needle to be reciprocated sufficiently to form the loops in the thread without the hook slipping out of the fabric, thus permitting the needle to be operated with greater speed than could be done with a needle having a short round hook with which the length of the strokes would necessarily be very short; a still further object of my invention is to provide a needle having an extremely short latch so that the point of the latch will not engage more than one straight thread when the latch is passed into and out of the fabric to form the loops; a still further object is to form the hook end of the needle with a curved portion which is slightly pointed, with the point thereof located nearer in longitudinal alignment with the open side of the hook than with the shank side of the hook. These together with various other novel features of construction and arrangement of the parts, which will be hereinafter more fully described and claimed, constitute my invention.

Referring to the accompanying drawings, Fig. 1 is a perspective view of my improved needle, greatly enlarged, and also showing a fabric which is to be repaired; Fig. 2 is a front

elevation of the needle with the latch in the open position as shown in Fig. 7; Fig. 3 is a transverse sectional view on line 3—3, Fig. 2; Fig. 4 is a transverse sectional view on line 4—4, Figs. 2 and 7; Fig. 5 is a side elevation of the needle showing it inserted into a loop of the fabric; and Figs. 6 to 9, inclusive, are views similar to Fig. 5 illustrating different steps in the operation of the needle to form the loops for repairing the fabric. 50

In the accompanying drawings in which like reference characters refer to like parts; 10 represents the needle consisting of a shank 12, having a handle 14 upon the upper end, and a hook 16 located upon the opposite end thereof. The hook 16 comprises a shank member 17 and a point member 18, which are located in parallel relation with each other, and a curved end portion having a lower end member consisting of a gradually curved portion 19 and a sharply curved portion 20 forming the extreme lower end 21 of the hook, which is located nearer in longitudinal alignment with the point member 18 than with the shank member 17, as clearly shown in Fig. 5. 60 65 The point of the hook member 18 terminates in spaced relation with the enlarged portion 22 of the shank, thus forming a throat 21 which is extremely narrow for reducing the possibility of more than one thread entering 70 75 the hook at the same time.

A latch 24 is pivotally mounted at the point 25 located in the enlarged bearing portion 22 of the shank. The latch 24 coacts with the point of the hook 18 in a manner similar 80 to other latch needles.

The novel feature of the present latch resides in the short construction of the point of the latch, so that it will not engage more than one straight or cross thread α of the fabric, as the needle is inserted into the fabric, as shown in Fig. 5, as the picking up of a thread by the point of the latch would tend to break the thread during the opening movement of the latch. The short construction 85 90

of the latch 24 is also of great advantage in forming a stitch due to the fact that when the needle is being withdrawn from the fabric, as shown in Fig. 8, the closing of the latch if it were the usual length would possibly engage two straight threads *a* and force them into the throat 21 of the hook as the latch closes down upon the latter, as shown in Figs. 8 and 9. By thus making the latch extremely short only one thread *a* will be engaged and forced into the hook, as shown in Fig. 9.

The needle 10 is provided with a stop 30 located above the latch 24, when in the open position, for limiting the distance the needle 15 may be inserted into the fabric. Said stop is so arranged that it engages the straight threads *a* of the fabric and prevents the needle being inserted far enough into the fabric 20 to allow the point of the latch 24 to engage any of the straight threads *a* of the fabric. Said stop comprises a plate 31, which may be formed in one piece or in two separate pieces secured upon or formed integral with the shank 12. Said plate 31 is positioned upon 25 one edge of the shank 12 and is positioned in a plane parallel with the latch 24 and the hook 16. The plate 31 forms a support for the lips 32 and 33 which form the stop 30. Said lips are of sufficient width to project 30 above the upper surface of the latch 24, when in the position shown in Fig. 7, and engage a straight thread *a* and stop it from sliding over the point of the latch. The lips 32 and 33 are positioned in spaced relation with each 35 other, thus forming a space for the entrance of the point of the latch between said lips when the latch is in the open position.

Said lips project from the plate 31 toward 40 the latch and are located in spaced relation with the shank 12 to form a space 34, which may be occupied by the looped thread *b* after it has passed over top of the latch into the space 34. The ends of the lips 32 and 33 45 are provided with V-shaped notches 35 for better engaging a straight thread *a*. Said lips overlap the point of the latch 24 when it is in the open position, thus preventing a straight thread *a*, which is located upon the upper surface of the latch, as shown in Fig. 50 7, from entering the space 34.

The lips 32 and 33 are positioned in spaced 55 relation with the sides of the latch 24, thus providing sufficient space between the lips and the point of the latch to permit a thread *b*, which is looped around the latch and the shank, to freely slide over the point of the latch between the lips and occupy the space 34 between the plate 31 and the latch; and 60 at the same time said lips will engage one or more cross threads *a* and prevent them from entering said space 34.

The operation of my improved needle is 65 as follows; the hook end 16 of the needle is inserted into the loop *b* of the fabric which is

to be knitted with the straight threads *a* for repairing the run or dropped stitch of the fabric. Fig. 5 shows the needle extended further into the fabric to a position in which the loop *b* has opened the latch and entered the throat 21 of the hook. The straight or cross thread *a* opens the latch as the needle is further inserted into the fabric. Fig. 6 illustrates that the latch 24 can swing from the closed position to the open position without the point of the latch interlocking with the straight threads *a* and breaking the same. The needle is further inserted into the fabric so that the loop *b* moves over the latch and passes between the lips 32 and 33 of the stop, thus allowing the loop *b* to pass over the point of the latch and occupy the space 34, as shown in Fig. 7.

The stop formed by the lips 32 and 33 engage the straight threads *a* and prevent them from passing over the point of the latch and also limiting the distance the needle may be moved downwardly into the fabric.

Fig. 8 illustrates the needle being withdrawn from the fabric. The loop *b* slides over the shank, engaging the latch and closing the same upon one thread *a*, thus helping to direct the latter through the throat 21, so that it will be engaged by the point of the hook 16. The loop *b*, as the needle is further withdrawn, slides over the latch 24 and over the hook 16, as shown in Fig. 9. A further upward movement of the needle causes the hook 16 to engage the cross thread *a*, which movement of the hook draws said cross thread through the loop *b*, thus completing the stitch in the usual manner. The successive stitches may be formed rapidly by simply moving the needle up and down through the fabric. The stop automatically 105 limits the downward movement of the needle and permits only a loop *b* to pass over the upper end of the latch. The upward stroke of the needle can be quite extensive due to the extremely long portions 17 and 18 of the hook, which portions form guides for directing the movements of the needle, and the novel shape of the lower portion of the hook 16 directs the needle over the next adjacent cross thread *a* at the beginning of a downward stroke to form a new loop, thus permitting the needle to be rapidly operated.

Various changes in the construction and arrangement of the parts may be made without departing from my invention.

I claim:

1. A needle for mending knitted fabric comprising, a shank, a hook upon the shank, a stop mounted upon the shank for engaging the fabric and limiting the distance the shank may be inserted into the latter, a latch having one end pivotally mounted upon the shank at a point midway between the point of the hook and the stop whereby the point of the latch will overlap the point of the hook 120

and overlap the stop when in the closed and open positions, respectively, and said stop positioned in spaced relation with the latch and with the shank for the free passage of a thread looped around the latch and the shank to a position beyond the point of the latch.

2. A needle for mending knitted fabric comprising, a shank, a hook upon the shank, a latch having one end pivotally mounted upon the shank with its free end overlapping the point of the hook to close the latter permitting a thread looped around the shank to pass over the latch, a plate mounted upon the shank located in spaced relation with the point of the latch when the latter is in the open position relatively to the hook, a lip upon said plate projecting toward said hook and overlapping the point of the latch when in the open position, and said lip having sufficient width projecting above the latch to form a stop for engaging a straight thread of the fabric extending over the latch and forming a stop for limiting the distance the shank may be inserted into the fabric.

3. A needle for mending knitted fabric comprising, a shank, a hook upon the shank, a latch having one end overlapping the point of the hook to close the latter permitting a thread looped around the shank to pass over the latch, a plate mounted upon the shank above the point of the latch when in the open position relatively to the hook, a lip upon said plate projecting toward said hook and overlapping the point of the latch when in the open position, said lip projecting above the latch forming a stop for limiting the distance the shank may be inserted into the fabric, and said lip positioned in spaced relation with the side of the latch whereby the point of the latch may swing past the lip permitting a looped thread to pass between the latch and the lip.

4. A needle for mending knitted fabric comprising, a shank, a hook upon the shank, a latch having one end pivotally mounted upon the shank with its free end overlapping the point of the hook to close the latter permitting a thread looped around the shank to pass over the latch, a plate mounted upon the shank above the point of the latch when in the open position relatively to the hook, a lip above said plate projecting toward said hook overlapping the point of the latch when in the open position, said lip having a notch formed therein for engaging a straight thread of the fabric for preventing said straight thread from passing beyond the point of the latch when in the open position, and said lip positioned in spaced relation with the side of the latch for permitting said looped thread to pass between the latch and the lip.

5. A needle for mending knitted fabric comprising, a shank, a hook upon the shank, a latch having one end pivotally mounted upon

the shank with its free end overlapping the point of the hook to close the latter permitting a thread looped around the shank to pass over the latch, a plate mounted upon the shank above the point of the latch when in the open position relatively to the hook, a lip upon said plate overlapping the point of the latch when in the open position and forming a stop for limiting the distance the shank may be inserted into the fabric, and said lip positioned in spaced relation with the shank for the free passage of a thread looped around the latch and around the shank to pass over the point of the latch into a position between the latch and the shank.

6. A needle for mending knitted fabric comprising, a shank, a hook upon the shank, a latch having one end pivotally mounted upon the shank and its free end overlapping the point of the hook to close the latter, a plate mounted upon the shank above the point of the latch when in the open position relatively to the hook, lips mounted upon said plate positioned at opposite sides of the point of the latch for the free passage of a thread looped around the latch and the shank into a position between the latch and said plate, said lips overlapping the point of the latch when the latter is in the open position forming a stop for engaging a straight thread for limiting the distance the needle may be inserted into the fabric relatively to the latch.

7. A needle for mending knitted fabric comprising, a shank, a hook formed upon the end of the shank, a latch having one end pivoted upon the shank and its free end movable in a plane in alignment with the plane of the hook and coacting with the latter, an upstanding member mounted upon the shank positioned upon the edge of the latter upon which the hook and latch are positioned, said member having lips positioned in spaced relation to each other, said lips diverging from each other and located at opposite sides of the latch when the latter is in the open position permitting a thread which is looped around the latch and the shank to pass between said lips and over the point of the latch, and said lips overlapping the point of the latch when in the open position forming a stop for engaging a straight thread on top of the latch and preventing it from passing over the point of the latch when the latter is in the open position.

8. A needle for mending knitted fabric comprising, a shank, a latch, said shank having an enlarged portion forming a bearing in which one end of the latch is pivoted, a hook of relatively long formation upon one end of said shank having its end terminating in close proximity to said enlarged portion of the shank, said latch having an extremely short formation with its free end terminating at the point of said hook, a plate mounted upon the shank located adjacent to the op-

- posite side of said enlarged portion of the shank relatively to the hook, lips mounted upon said plate extending toward said latch in spaced relation with said shank, said lips positioned in spaced relation with each other
- 5 to receive the point of the latch between them when the latch is in the open position relatively to the hook and allow a looped thread to pass over the point of the latch, said lips having sufficient width to form a
- 10 stop projecting above the top surface of the latch when the latter is in the open position for engaging a straight thread and preventing it from passing over the point of the latch when in the open position.

15 In testimony whereof I affix my signature.

JOSEPH MESSING.
